UNITED STATES PATENT OFFICE

142,883

DESIGN FOR A GOOSENECK COUPLING FOR A DRAWN VEHICLE

William E. Martin, Kewanee, Ill.

Application September 6, 1944, Serial No. 115,208

Term of patent 14 years

(Cl. D14—6)

To all whom it may concern:

Be it known that I, William E. Martin, a citizen of the United States, residing at Kewanee, in the county of Henry and State of Illinois, have invented a new, original, and ornamental Design for a Gooseneck Coupling for a Drawn Vehicle, of which the following is a specification, reference being made to the accompanying drawing, forming a part thereof.

In the drawing:

Fig. 1 is a side elevational view of a gooseneck coupling for a drawn vehicle showing my new design;

Fig. 2 is a front elevational view thereof; and
Fig. 3 is a perspective view thereof.

I claim:

The ornamental design for a gooseneck coupling for a drawn vehicle, substantially as shown.

WILLIAM E. MARTIN.
